UNITED STATES PATENT OFFICE

DAVID H. GOODWILLIE, OF TOLEDO, OHIO, ASSIGNOR TO THE EDWARD FORD PLATE GLASS COMPANY, OF ROSSFORD, OHIO, A CORPORATION OF OHIO

LEER-OVEN ARRANGEMENT

Application filed September 12, 1927. Serial No. 218,997.

This invention relates to a leer oven arrangement adapted to be located at the hot or charging end of a leer used in the annealing of sheet or plate glass.

5 In the manufacture of sheet or plate glass, whether by the continuous process in which the sheet is produced in a continuous ribbon, or by the intermittent process in which a series of individual plates or sheets are produced, it is necessary to anneal the sheets or plates after they are formed, in order to remove or equalize the internal strains which always exist. This is done by passing the sheets or plates through a series of ovens, the 10 first of which is maintained at a temperature at or above the critical or annealing temperature of the glass being operated upon, each succeeding oven being slightly lower in temperature than the preceding one. From the 15 last of these ovens the glass is passed into a cooling chamber or runway, the entering end being slightly cooler than the last oven and the temperature at the discharge or pull-out end being approximately that of the 20 surrounding atmosphere. This combination of ovens and cooling chamber is known to the 25 trade as a leer.

In the process of forming individual sheets or plates, it has been the practice to push them 30 from the casting table on which they have been formed or deposited into the first or hottest of the annealing ovens by means of a stowing tool. Owing to the high temperature of the ovens, which ranges from about 35 1300° F. in the first oven down to about 900° F. in the last oven, from which the glass is discharged into the runway, it is quite important that the stowing tool be withdrawn 40 from the oven after each operation, in order to prevent it from becoming warped by the heat. Heretofore, it has been the general custom, in order that the stowing tools could be conveniently manipulated, to arrange the 45 ovens in zigzag fashion so that as each plate is shoved from one oven to the next it moves in a path at right angles to its movement during the preceding step. This necessitates the provision of a separate stowing tool for each 50 oven, in addition to the stowing tool which shoves the plate from the casting table into the first oven.

With the above facts in mind the object of the present invention is to provide a simplified arrangement of ovens, which requires a 55 smaller number of stowing tools for carrying out the process, and in addition thereto makes it feasible to cast two plates at a time, providing duplicate series of ovens from which the plates are discharged alternately into the 60 entrance to the runway. The specific construction and arrangement of ovens embodied in the present invention, together with the arrangement of the stowing tools used in connection therewith will be more particular explained in connection with the accompanying 65 drawing, which illustrates the invention in its preferred form and which comprises a horizontal section through the front portion of the leer runway and the series of ovens 70 leading thereto.

The front end of the leer runway is indicated at 1 and directly in front of this runway is an oven 2. Connected to opposite sides of the oven 2 are series of ovens 3 and 4 75 respectively extending in straight lines parallel to the axis of the runway 1. The first oven of each series is provided with an entrance indicated at 5 and 6 respectively through which the glass is stowed. A track 80 7 extends transversely in front of the leer and, in the present embodiment of the invention, two casting tables 8 and 9 are provided, upon which the glass is cast as it passes from the rolls 10. With the tables arranged in 85 front of the rolls 10, two plates may be cast and then cut apart and the tables brought into position in front of the entrances 5 and 6 respectively.

For each table there is provided a stowing tool 11 having two pushers 12 and 13 arranged with the distance between them somewhat greater than the width of the glass. At the rear end of each series of ovens is a stowing tool 14 having a glass engaging member 15 adapted to be inserted through the door 16 and to engage behind the glass and to draw it into the last oven of the series. At the outer side of this last oven is a stowing tool 17 provided with a pusher 18 adapted to be 90 95 100

inserted through an opening 19 to shove the glass into the last oven 2 at the entrance to the runway 1. In front of the oven 2 there is a stowing tool 20 similar to the stowing tools 11, having pushers 21 and 22 respectively and adapted to be inserted through a door 23 to stow the glass into the runway.

In the operation as carried out in accordance with the present invention, two plates 10 are formed and delivered on the casting tables to positions indicated at *a* and *a'* respectively. The cycle of operation will be the same for both series of ovens. The moves must be so timed that a plate is delivered to 15 the oven 2 at the entrance to the runway alternately from each series of ovens 3 and 4. The two plates are delivered by the tables at intervals of seven to eight minutes and to both series of ovens at about the same time. 20 The plates are stowed into the oven 2 at intervals of three and one-half to four minutes, and the moves must be so timed as to produce this result.

After the glass sheet or plate is in the position indicated at *a*, the tool 11 is advanced 25 until the pusher 12 engages the glass and pushes it into the first position *b* in the series of ovens. At the expiration of the proper time, in this case three and one-half to four 30 minutes, the tool 11 is again started and pushes the plate from position *b* to position *c*.

Upon the arrival of the next plate in front 35 of the entrance 6 it is pushed into the vacant space previously occupied by the first plate by means of the pusher 12, and at the same time the pusher 13 engages the first plate and pushes it into position *d*. The tool then returns to its original position, the pushers 12 and 13 being raised during the return stroke 40 so that they are suspended out of contact with the oven bottom and the sheets of glass resting thereon.

Before the arrival of the third plate in front of the entrance 6, the second plate is 45 moved into position *c* leaving the first oven vacant for receiving the third plate which is now stowed therein by the rear pusher 12, the forward pusher 13 making an idle stroke during this operation.

50 Shortly after this operation is completed, say two minutes, the first plate is moved to position *e* by means of the stowing tool 14. During the entering stroke of this tool it is held out of contact with the oven bottom and 55 at the completion of the stroke is dropped into contact with the oven bottom behind the edge of the first plate. Upon the return or outward stroke of this tool, the first plate is advanced to the position *e*.

60 At the same time or immediately after the last described move, the tool 11 is moved through the door 6 and the pushers 13 and 12 are dropped into contact with the rear edges of the second and third plates. By 65 continuing the motion these plates are moved

one position forward, leaving the first place vacant for the reception of the next plate.

The next move is to stow the fourth plate into the first oven so that the series of straight line ovens 4 is now full of plates.

70 The first plate is then advanced from position *e* to position *f* by means of the tool 17, which may be of the most ordinary type, working from the side of the oven and traveling back and forth with the pusher 18 always 75 in contact with the bottom.

76 While the plates are being intermittently advanced through the set of ovens 4, plates will also be advanced through the set of ovens 3 and will successively occupy positions *b'*, *c'*, *d'* and *e'*. The movements in one set of chambers alternate with the movements in the other set.

80 Plates will be moved into the oven 2 alternately from the positions *e* and *e'* and are then advanced successively to the positions *g* and *h*, at proper intervals, say three and one-half to four minutes, by means of the pushers 21 and 22 on the stowing tool 20. From the position *h* the plates are advanced 85 step by step to positions *i*, *j*, *k*, etc., in the runway, by means of the usual mechanism, which is entirely independent of the stowing mechanism.

86 This invention is of particular merit in the manufacture of two plates of glass from one casting of the contents of a glass pot. It 90 enables two plates of glass to be pushed into parallel ovens and then brought together in a runway common to both plates, making it possible to construct and use one runway for both plates instead of separate runways for each sheet, thus avoiding the greater expense of building two runways and avoiding the complication of pushing plates through the length of a straight-line oven on to the runway rods. In order to avoid the additional expense of constructing two runways and the mechanical difficulties of straight-line leers, it is essential that two sets of ovens 95 be used with the runway common to both. If two sets of zigzag ovens are used (which may be done) the distance of travel for the first plate from the forming mechanism past the first ovens to entrance position in the 100 second set of ovens will be so great as to allow the plate on its casting table to warp and chill. With my system of parallel ovens the distance of travel which the first plate is required to make will be less by the width of 105 two ovens.

110 From the foregoing description, it will be seen that I have devised a simplified arrangement of ovens which may be substituted for the crude zigzag arrangement used for many 115 years, and which also makes it possible to carry out the annealing process with fewer stowing machines. The operation is also facilitated by the use of two parallel series of 120 ovens, from which the plates are alternately 125

delivered to a position in front of the runway or cooling chamber. While the plates may be advanced step by step from the casting table to the runway by any stowing tools suitable for the purpose, it is preferred to use tools of improved construction, which have been devised especially for that purpose, and which are described and claimed in separate applications.

10 What I claim is:

1. The combination with a leer runway, of a series of ovens arranged in a straight line in front of and parallel to the runway, an intermediate oven directly in front of the runway and adjacent the last oven of said series, a stowing tool in front of said series to move the plates rearwardly in the front portion of said series, a stowing tool in rear of the series for pulling the plates to complete their movement into the rearmost oven of said series, a stowing tool at one side of said rearmost oven for moving the plates into said intermediate oven, and a stowing tool in front of said intermediate oven to move the plates into the runway.

2. The combination with a leer runway, of a series of ovens arranged in a straight line in front of and parallel to the runway, an oven directly in front of the runway, a stowing tool in front of said series and provided with a plurality of pushers spaced apart sufficiently to engage and push a corresponding number of separate plates rearwardly in the front portion of said series, a stowing tool in rear of the series for pulling the plates separately into the rearmost oven of said series, a stowing tool at one side of said rearmost oven for moving the plates into the oven directly in front of the runway, and a stowing tool in front of said last mentioned oven to move the plates into the runway.

3. In a leer, the combination of two parallel series of ovens arranged in a straight line, an intermediate oven between the rearmost ovens of the two series, a runway in rear of said intermediate oven, means operable from the front of each series to move separate plates rearwardly through a part of the series, means operable from the rear of each series to complete the rearward movement of the plates, laterally disposed means for moving the plates thence into the intermediate oven, and means in front of the intermediate oven to move the plates into the runway.

4. In a leer, the combination of two series of ovens spaced apart and each arranged in a straight line, an intermediate oven between the rearmost ovens of the two series, a runway in rear of said intermediate oven, a stowing tool in front of each of said series and provided with a plurality of pushers to engage and push a number of separate plates rearwardly in the series of ovens, a stowing tool in rear of each series for pulling the plates to complete their movement into the

rearmost oven of the series, opposite laterally disposed stowing tools for moving the plates alternately from the rearmost ovens of the series into said intermediate oven, and a stowing tool in front of said intermediate oven to move the plates therefrom into the runway.

5. In a leer, the combination of a series of ovens arranged in a straight line, an intermediate oven adjacent the side of the rearmost oven of said series, an oven in rear of said intermediate oven, a runway in rear of and in alinement with the two last mentioned ovens, a stowing tool in front of said series of ovens and provided with a plurality of pushers for engaging and pushing a number of separate plates rearwardly within the series of ovens, a stowing tool in rear of said series to complete the movement of the plates into the last oven of said series, a laterally disposed stowing tool for moving the plates into the intermediate oven and a stowing tool in front of said intermediate oven and having two pushers for moving the separate plates onto the runway.

6. In a leer, the combination of two spaced series of ovens, each arranged in a straight line, an intermediate oven between the rearmost ovens of the two series, an oven in rear of said intermediate oven, a runway in rear of said last mentioned oven, a stowing tool in front of each of said series and provided with a plurality of pushers spaced apart for engaging and pushing a corresponding number of separate plates rearwardly within the series of ovens, a stowing tool in rear of each series for pulling the plates to complete their movement into the rearmost oven of the series, stowing tools at the outer sides of the rearmost ovens of the series for alternately moving the plates from said rearmost ovens into the intermediate oven and a stowing tool in front of said intermediate oven and provided with two pushers for completing the movement of the plates onto the runway.

7. The combination with a series of ovens arranged in a straight line, a casting table movable to a position in front of the first oven of the series, means operable from the front of the first oven of the series to move separate plates from the casting table rearwardly through a part of said series, means operable from the rear of said series to move the plates successively into the last oven of the series, and means operable from the side of said last oven to discharge the plates laterally therefrom.

8. In a leer, the combination of two parallel series of ovens, each arranged in a straight line, an intermediate oven between the rearmost ovens of the two series, casting tables movable into positions in front of the respective series of ovens, means operable from the front of each series for moving plates successively from the casting table through

a portion of the series, means operable from the rear of each series for completing the movement of the plates into the rearmost oven thereof, and means operable from the outer sides of the rearmost ovens to move plates alternately therefrom into said intermediate ovens.

9. In an annealing apparatus, a glass runway, a pair of ovens cooperating therewith and located on opposite sides thereof, and each containing a plurality of glass sheets, substantially symmetrically disposed stowing mechanisms cooperating with said ovens, and stowing heads cooperating with said stowing mechanisms, certain of said heads being operative for pushing individual glass sheets while other of said heads are operative for pulling the same individually.

10. In a glass annealing apparatus, the combination with a plurality of straight line ovens having a common runway, of opposed stowing mechanisms for moving the glass through said ovens.

In testimony whereof I have hereunto signed my name to this specification.

DAVID H. GOODWILLIE.
